FIG. 1

FIG. 2

FIG. 3

FIG. 4

FIG. 5

FIG. 6

FIG. 1 is a rear elevational view of a box showing my new design;

FIG. 2 is a front elevational view;

FIG. 3 is a side elevational view taken from the right of FIG. 2, the opposite side being a mirror image of the side shown;

FIG. 4 is a bottom plan view;

FIG. 5 is a top plan view; and

FIG. 6 is a front elevational view thereof with the cover raised and the tear strip removed.

The broken lines in FIGS. 1 and 2 indicate score lines.

Characteristic features of the present invention reside in the particular flat top and scored line arrangement on the front of the box having a curved bottom with parallel sides extending to the very top of the filter dispenser

and include the notch arrangement best shown in FIGS. 5 and 6 at the top of the box.

I claim:

The ornamental design for a box, as shown and described.
